VACUUM CLEANER ATTACHMENT

Philip Gasner and Sigmund Gasner, New York,
 N. Y., assignors, by mesne assignments, to
 Hygienic Dust Bag Corporation, New York,
 N. Y., a corporation of New York

Application January 23, 1930, Serial No. 422,732

3 Claims. (Cl. 183—51)

Our invention relates to a new and improved vacuum cleaner attachment.

One of the objects of our invention is to provide an improved vacuum cleaner attachment of the type shown in U. S. Patent No. 1,729,103.

Another object of our invention is to provide a vacuum cleaner attachment which shall provide a collecting bag of large size.

Another object of our invention is to provide a collecting bag which can be conveniently coupled to a vacuum cleaner.

Other objects of our invention will be set forth in the following description and drawings which illustrate a preferred embodiment thereof, it being understood that the above general statement of our invention is intended to generally explain the same and not to limit it in any manner.

Fig. 1 is a side elevation showing the improved collecting bag located in an outer bag made of cloth or the like.

Fig. 2 is a side elevation showing the collecting bag alone.

Fig. 3 is a front elevation of a second type of collecting bag.

Fig. 4 is a sectional view on the line 4—4 of Fig. 3.

Fig. 5 is a general perspective view showing the use of the invention.

Fig. 6 is a view similar to Fig. 1, showing a different type of coupling.

Fig. 7 is a sectional view on the line 7—7 of Fig. 6.

Fig. 8 is a sectional view on the line 8—8 of Fig. 7.

Fig. 9 is a cross section through the neck of the cloth bag, along the line 9—9 of Fig. 1.

The attachment is intended to be applied to any vacuum cleaner 1 having an outlet nozzle 2 and a handle 3. A cloth bag 4 of any suitable type may be provided with an ear 6, by means of which it can be connected to the handle 3 by a member 7a. The bag is adapted to be opened. Normally however, its upper edge is folded over, as Fig. 9 shows, and is inserted into a U-shaped clamp 17, secured by button head bolts 18 and screws 19, similar to the closing device shown in former Patent No. 1,729,103. This feature however may be varied in any convenient way, for instance Fig. 6 indicates the way of closing the bag opening by means of two series of interlocking chain links 20, closed or opened by a movable shackle 21, with a handring 22 attached to it; a well known locking device used, for tobacco pouches, blouse fronts, shoes, etc. which device however forms no specific part claimed for this invention,

and is therefore not especially detailed. This bag 4 is provided with an inner hose 5, which communicates with a coupling 7. This coupling 7 can be connected to the outlet nozzle 2 of the vacuum cleaner so that the air current which is forced out of said nozzle 2 is also forced through the hose 5. The hose 5 may be made of any suitable fabric provided with any suitable lining. The hose 5 is preferably permeable to air although it may be made substantially impervious to air if desired. If the hose 5 is made permeable to air, the interior thereof is made sufficiently smooth, and the hose 5 is made sufficiently narrow so that the current of air and dust passes through the hose 5 without depositing the dust on the walls thereof. We have found it suitable to make the hose 5 2 1/4 inches in diameter and to make it of rubber or the like having a lining made of rubber or the like. The bag 8 is made of suitable paper, which is preferably permeable to air. It is provided with a mouth member 9 which can be made of cardboard or other material having sufficient stiffness to enable the mouth of the bag to be readily connected to the coupling provided at the upper end of the hose 5. However, this mouth member 9 may be readily collapsed into flat form, so that the bag 8 may be shipped or stored in flat form. The operation of this device is substantially the same as that shown in our previous device illustrated in U. S. Patent No. 1,729,103. The current of air and dust passes through the hose 5 with considerable velocity so that substantially all the dust is projected into the bag 8. If some of the air escapes in the hose 5, this does not cause dust to be deposited to any injurious extent upon the inner wall of the hose 5 for the reasons before specified. The air current leaks out of the pervious paper bag as it passes through the top portion thereof, at which portion the air current changes in direction to enter the lower part of the bag. The air current passes out of the bag, leaving the dust and dirt deposited therein. By making the hose 5 at the top of the paper bag sufficiently permeable to air, enough air can leak out of the same to prevent the paper bag from bursting. This makes it unnecessary to support the walls of the paper bag 8 by the wall of the cloth bag 4, so that, as shown in Fig. 1, there is a substantial space between the paper bag 8 and the inner wall of the cloth bag 4. The only purpose for using the cloth bag 4 is to prevent the paper bag 8 from being accidentally torn or otherwise injured.

In the embodiment shown in Figs. 3 and 4, the paper bag 8a is also made of permeable paper,

and it is provided with a mouth 15 having a stiffening member 9a. The paper bag may be made of two or more pieces suitably connected in any manner as by stitching or the like. The cloth bag 4 may be a side-opening bag of the well known type so that the paper collecting bag may be readily inserted and connected to the coupling member located at the top of the hose 5.

It will be noted that the coupling member 7 which cooperates with the lower end of the hose 5, projects from the outer protective bag 4. Hence, the bag can be coupled to the outlet nozzle in the ordinary manner.

One of the features of our invention is that the hose 5 is sufficiently narrow to cause the air current to pass through the same with high velocity, so that the dust is swept along instead of being deposited upon the inner wall of the hose to clog the pores thereof.

The hose 5 could be made of impermeable material, such as rubber-lined fabric, up to or nearly up to the coupling member which connects the same to the permeable bag 8. This increases the velocity with which the dirt passes through the hose 5, so that it is carried around the upper bent portion of the bag 8. This feature is particularly useful where the vacuum cleaner has low suction power. The coupling shown in Figs. 6-8 comprises an outer metal collar 11, having an inner metal collar 10 spaced therefrom. The mouth 9 of the bag 8 fits snugly between the collars 10 and 11, so as to substantially or completely eliminate leakage of air. The outer collar 11 is provided with a clamp 13 hingedly connected thereto at 14. The clamp 13 is forced to the operative position by means of a blade spring 16. The clamp 13 is provided with a point or points 12 which extend through a suitable opening in the outer collar 11, so that the point or points 12 can penetrate the mouth of the bag 8 and hold the same firmly but releasably in position.

We have shown a preferred embodiment of our invention, but it is clear that numerous changes and omissions could be made without departing from the spirit of our invention.

We claim:

1. In a vacuum cleaner attachment comprising an outer protective bag having a hose located therein, said hose being provided with a coupling which projects from said outer bag, said outer bag being adapted to be opened, and a bag made of paper which is permeable to air, said paper bag having a mouth which is adapted to be coupled to the upper end of the hose, said mouth making an angle with the main body of the bag, 10 said hose being permeable to air and being sufficiently narrow to prevent any substantial deposit of dust upon the inner walls thereof, the body of said bag depending below said mouth when the device is in use and said mouth being upwardly directed when the device is in use.

2. A vacuum cleaner attachment comprising an outer protective bag having a hose located therein, said hose being provided with a coupling which projects from said outer bag, said outer 20 bag being adapted to be opened, and a bag made of paper which is permeable to air, said paper bag having a mouth which is adapted to be coupled to the upper end of the hose, said mouth making an acute angle with the main body of 25 the bag, the body of said bag depending below said mouth and forming a dust receiver when the device is in use, said mouth being upwardly directed when the device is in use.

3. A vacuum cleaner attachment comprising 30 an outer protective bag having a hose located therein, said hose being provided with a coupling which projects from said outer bag, said outer bag being adapted to be opened, and a bag made of paper which is permeable to air, said paper 35 bag having a mouth which is adapted to be coupled to the upper end of the hose, said mouth making an acute angle with the main body of the bag, the body of said bag depending below said mouth and forming a dust receiver when the 40 device is in use, said mouth being upwardly directed when the device is in use, said mouth having a mouthpiece member.

PHILIP GASNER.

SIGMUND GASNER.
